JOHN J. MULVEY, OF SEATTLE, WASHINGTON

FLOUR AGITATOR FOR EXPOSING FLOUR TO THE ACTION OF A BLEACHING GAS

Application filed July 19, 1927. Serial No. 206,919.

My invention relates to a flour agitator and for exposing flour to the action of a bleaching gas. More particularly my invention relates to a whirlwind agitator used in the manufacturing of flour and to the process of aerating and bleaching said flour.

In the manufacture of flour from wheat a device with an agitator is used in connection with the very last step of treatment. Before coming to the agitator the flour has been ground and is more or less in a dampened condition and heated due to the action of grinding. It is then put into a device commonly known as an agitator wherein it is intermixed with chlorine gas or other bleaching agents. The agitators heretofore constructed consist of a large drum which is filled to a large extent and in which are placed paddles moving at a relatively low speed to thoroughly agitate and mix the flour with a bleaching gas such as chlorine gas admitted to said drum. This device is slow in operation and is relatively costly to manufacture, the weight of the flour agitated requiring the paddles to be made of metal.

A primary object of my invention is to provide an agitator in which the paddles will operate at a high rate of speed and have a method of operation which permits of their being constructed of wood.

A further primary object of my invention is to provide an agitator which will supply proper agitation of the flour in the presence of a bleaching gas such as chlorine gas, and which so exposes the flour to the said gas as to very materially reduce the amount of gas required. A further primary object of my invention is to provide an agitator which operates to cool the flour and to dry it as well.

A further primary object of my invention is to provide an agitator which operates upon each individual particle of the flour as contrasted with operating upon a large mass of flour.

Flour has the property of tending to choke the passageway through which it passes. Particularly is this true when in the heated and dampened condition (being wet when ground) in which it comes, during its passage through the various treating mecha-

nisms, to the agitator device, which constitutes the subject matter of this invention. Guarding against choking should be afforded even when the device fails to operate, by reason of accident such as when the paddles are stopped due to the slipping off or breaking of the belt and the feeding of the flour to the device is continued for some time before being shut off. A primary object of my invention is to provide an agitator which overcomes all these difficulties, and one which will be most economical in operation not only as respects quantity capable of being handled and gas required, but also as respects power consumed.

The above mentioned general objects of my invention, together with others inherent in the same, are attained by the device illustrated in the following drawings, the same being a preferred exemplary form of embodiment of my invention, throughout which drawings like reference numerals indicate like parts:

Figure 1 is a view in front elevation of a device embodying my invention with parts broken away.

Fig. 2 is a view in end elevation of the same.

Fig. 3 is an enlarged view of one of the paddles of said device, and

Fig. 4 is a cross-sectional view through said paddle.

Two separate compartments 5 and 6 having partition 7 there-between are provided. The two compartments are provided to give greater capacity of flour treated for the same driving mechanism. These compartments are preferably vertically disposed and have glass doors or windows 8 therein so that the operation upon the flour is in full view and readily inspected. The paddle wheels 9, 10, 11, 12, 13, 14, 15, 16 and 17 are all alike. The paddle wheels are arranged in each compartment, one above the other in offset relation as illustrated in Fig. 2 having the axes of alternate paddles in parallel vertical planes. These paddle wheels are mounted respectively on shafts 18, 19, 20, 21, 22, 23, 24, 25 and 26, which are provided respectively with pulleys 27, 28, 29, 30, 31, 32, 33, 34 and 35, over which pulley belt 36

5 operates. This belt engages the pulleys moving in an upwardly direction so that the paddles have the direction indicated by the arrows. The compartments 5 and 6 have respectively inlets 37 and 38, and outlets 39 and 40. Each compartment is provided with a gas intake 41. The paddle wheels consist of arms 42 and 43, having wooden blades 44 mounted thereon.

10 The mode of operation of the device embodying my invention is as follows:

The flour falls by gravity or other suitable conveyance through inlet 38, for example, into compartment 6 where it is acted upon by paddle wheels 9 and 10 and drawn there-between into the part 45 of the chamber 6, 45 representing that part of compartment 6 disposed between paddle wheels 9 and 11 constituting a local zone of agitation, these paddle wheels having sufficient clearance so that there is no danger of their striking. Other similar zones 46, 47, 48, 49, 50 and 51, are disposed below, having passageways 55, 56, 57, 58, 59, 60 and 61 between said paddles.

25 Entering zone 45 the flour strikes upon paddle wheel 11 which is moving in a direction opposite to the oncoming flour in part 45, i.e., the flour entering through passageway 54. In other words, the action of paddle wheel 11 tends to reverse the direction of the flour and in this wise thoroughly agitates and separates the flour into its component particles. The two paddle wheels 9 and 10, it will be noted, tend to act as a valve in inducing the flour to

30

35 the lower portions of the compartment, i. e., the two paddle wheels 9 and 10 are moving together on their adjacent faces against which the flour impinges. The flour meets the same condition in passing through pas-

40 sageways 55, 56, 57, 58, 59, and 60. Belt tightener 52 is provided to impart the necessary degree of tightness to belt 36. Driving belt 53 in addition to belt 36 is provided

45 to supply driving means. The recess provided below each paddle wheel constitutes a local area of agitation or whirlwind center. It will be noted that the direction of rotation of the paddle wheel below is contrary to that

of the paddle wheel directly above, and, therefore, the air in the various zones pockets, or sections below the paddle wheels is given a violent rotary movement that is exceptionally well adapted to impart the agitation desired. Also it will be noted that

55 relatively small quantities of the flour are operated upon at a time, that is, the quantity in each given pocket or recess below each paddle wheel is relatively small in a given time but it is there violently acted upon by

time, but it is there violently acted upon by the whirlwind movement of the air contained in the particular pocket. In this wise the gas is most efficiently brought into contact with each and every particle of the flour which is thoroughly dried by the process as well, i.e., the mode of operation involves

65 well, i. e., the mode of operation involves

each particle of flour as it were, and operating upon it alone, thereby effecting not only the desired agitation and exposure to the gas but also a drying effect. Exposure, particle by particle, of the flour to the gas provides for the most even distribution and efficient use of said gas, reducing the amount required for a given quantity of flour by a third. In fact, a better color is imparted to the flour with less gas, the exposure being so much more thorough, as well as the aeration. If, for any reason, the paddles are not caused to revolve, the flour will simply run through by gravity and all choking avoided due to the preferred vertical position of the machine. 70 75 80

Besides being used as an agitator, the device embodying my invention may also be used as a wheat scourer.

Obviously, changes may be made in the form, dimensions, and arrangement of the parts of my invention, without departing from the principle thereof, the above setting forth only a preferred form of embodiment. 85

I claim:

1. A device of the character described embodying a vertically disposed compartment; flour inlet and outlet ports in the upper and lower end portions respectively of said compartment; a plurality of paddle wheels revolvably mounted in said compartment substantially in a plurality of vertically disposed series in laterally off-set relation; means to operate the paddle wheels in one vertical series in one direction and those in the other vertical series in the opposite direction, the paddle wheels of one set rotating in opposite direction to that of the adjacent paddle wheel of the other set; and a bleaching gas inlet port in said compartment. 90 95 100

2. In a device of the character described 105
the combination of a vertically disposed compartment; a plurality of paddle wheels re-
movably mounted in said compartment sub-
stantially in a plurality of vertically dis-
posed series in laterally off-set relation; and
means to operate the paddle wheels in one 110
vertical series in one direction and those of
the other vertical series in the opposite direc-
tion, the paddle wheel of one set rotating in
opposite direction to that of the adjacent 115
paddle wheel of the other set.

In witness whereof I hereunto subscribe
my name this 13th day of July, A. D. 1927.
JOHN J. MULVEY.
